INTERLOCKING SHINGLE

Stuart Parmelee Miller, Scarsdale, N. Y., assignor
to The Barrett Company, New York, N. Y., a
corporation of New Jersey

Application January 31, 1935, Serial No. 4,260

5 Claims. (Cl. 108—7)

This invention relates to shingles and more particularly to interlocking composition shingles.

One object of this invention is to provide a shingle which is particularly adapted for re-roofing purposes; which can be cut from a sheet of felt base roofing material without substantial waste and which can be readily laid with other like elements in overlapping, diagonal courses to produce an efficient roof covering of decorative appearance.

Another object is to provide an interlocking shingle adapted to be laid with other like shingles in overlapping courses with the side corner portions of each pair of shingles in the same horizontal course overlapping and underlapping and having a locking projection on the lower corner adapted to pass under the side portion of only one underlying shingle so that the lower corner is thus locked down to provide a waterproof roof covering. Other objects and advantages of this invention will appear from the following detailed description.

Shingles, the lower corners of which are provided with projecting portions adapted to interlock with underlying elements and intended to be laid with the side corner portions overlapping and underlapping, are well known. In such shingles the locking projections in the corners were designed to lock with a pair of underlying shingles requiring the flexing of both underlying shingles to permit the locking of a single overlying shingle therewith. This invention is in the nature of an improvement on such shingle elements in that it provides a shingle of simple construction which can more readily be applied in interlocking relation with other like elements and which has the locking projection at the lower corner designed to pass under the side portion of only one underlying shingle to produce an efficient roof covering.

In the accompanying drawing forming a part of this specification and showing for purposes of exemplification a preferred form of this invention but without limiting the claimed invention to such embodiment:

Fig. 1 is a plan view of a strip of shingle material indicating a layout for cutting the shingle of Fig. 2;

Fig. 2 shows a plan view of a shingle embodying this invention; and

Fig. 3 shows a fragmentary plan of a number of shingles of Fig. 2 arranged upon a roof or other surface.

Referring to the drawing, 11 indicates a shingle having substantially straight sides 12, 13, 14 and

15 defining a substantially square body portion. Side edge 13 is formed with a cut-out portion providing a notch 16 and the boundaries of the corner of the shingle formed by the juncture of converging side edges 14 and 15 are defined by a 5 broken edge constituted of the relatively short edge portions designated by the reference numerals 17, 18, 19, 20 and 21. Edges 17 and 18 cooperate to form notch 23 which is adapted to cooperate with notch 16 of an adjacent shingle 10 in the same horizontal course in a manner to be more completely described hereinafter. Curved edge 20 cooperates with straight edge 21 to form locking recess 25 the function of which is more completely set forth hereinafter.

Formed on the lower corner of the shingle and projecting from the rectangular outline thereof defined by side edges 12, 13, 14 and 15 is a substantially triangular locking projection designated as a whole by reference numeral 27. Locking 20 projection 27 is defined by straight edge 28 in line with edge 12 and at right angles to edge 15, edge 30 extending at an acute angle to edge 28, slightly curved edge 32, and comparatively short straight edges 33 and 34 which cooperate with 25 edge 12 of the shingle body to form locking recess 35. Triangular locking projection 27 is shaped as shown to permit cutting of the shingle elements from a roofing sheet with a minimum of waste, to permit ready interlocking engagement of the projection and the locking recess 35 with a shingle of an underlying course, and to enhance the decorative appearance of the resultant roof as will appear more fully hereinafter.

Fig. 1 discloses the cutting of the shingle elements of Fig. 2 from a sheet of material of a width sufficient to produce two of the elements in cutting position. It will be understood that the fabric or base from which the shingles are cut may be of any desired width, preferably of a 40 width sufficient to produce two, four or any desired even number of such elements.

In Fig. 2 the longitudinal edges 36 of the fabric or base define the side edges 13 of each shingle, the cutaway portions along the edges 36 corresponding to notches 16. Transverse cuts 37 define side edges 12 and 14 and longitudinal cuts 38 define the side edges 15 of the shingle elements. The interlocking portions of contiguous shingles are defined by diagonal cuts 40, broken 50 cuts designated as a whole by the reference numeral 41 and cut-out portions 43, 44. Cut-out portions 43 and 44 are represented by the shaded areas in Fig. 1. The side edges of cut-out portions 43 define aligning notch 23 and locking re- 55

cess 35 associated with projection 27. The side edges of cut-out portion 44 define locking recess 25 located near the horizontal corner of the shingle shown in Fig. 2. It is pointed out that 5 the relatively small amount of material cut out of the notches 16 and out of the cut-out portions 43 and 44 represents the only waste involved in cutting the shingles from a roofing base.

With reference to Fig. 3, it will be noted that 10 the shingles are adapted to be laid in courses, each edge being inclined to the horizontal direction of the roof, one diagonal of each shingle being at right angles to the longitudinal direction of the roof.

15 In applying the shingles, shingle A is laid with the corner defined by converging sides 12 and 13 in overlapping relation to the corner portion of shingle B which is provided with locking recess 25. Notch 16 of shingle A cooperates with notch 20 23 of shingle B to determine the proper horizontal and vertical position of the shingles with respect to each other. When properly laid, side edge 12 of shingle A is parallel to, but spaced a short distance from edge 21 of locking recess 25 of shingle B. It will be noted that by this arrangement, side edge 12 of an overlapping shingle cooperates with side edge 21 of recess 25 of an underlapping shingle to form a relatively narrow pocket as more clearly illustrated at 46 30 in connection with shingles B and D at the right-hand side of Fig. 3. After the shingle A has been placed in position a nail is driven through the corner of this shingle which overlaps shingle B. This nail, it will be noted, 35 passes through the underlying corner of shingle B and also through the upper corner of the adjacent shingle in the adjacent underlapping horizontal course. Thus, even though only one nail per shingle is used, each shingle is anchored by 40 a nail at three points, i. e., at each horizontal corner and the top vertical corner.

Reference character C indicates a shingle of the adjacent overlapping horizontal course. Shingle C is applied by insertion of the portion 45 of locking projection 27 adjacent locking recess 35 beneath the side edge 15 of shingle B, the recess 35 interlocking with the pocket defined by edges 12 and 21 of shingles A and B respectively. Shingle C is then turned about the short 50 edge 34 thereof as a pivot until the edge 28 abuts against edge 12 of shingle A and notch 16 is in substantial alignment with side 14 of shingle B. It will be noted that the edge 28 and notches 16 and 23 serve as aligning guides or position indicating means which determine the position of 55 each shingle when laid. In the resultant roof, shingle A overlaps shingle B and shingle C overlaps a portion of both shingles A and B and underlaps a portion of only shingle B, thereby 60 providing a firm interlock between the three shingles with the aid of only a single locking projection, viz., the projection 27. The portion of locking projection 27 of shingle C, which is not overlapped by shingle B, constitutes a substantially triangular exposed portion within the angle defined by edge 12 of shingle A and the edge 15 of shingle B, thereby lending the resulting roof an improved ornamental appearance.

It will be noted that applicant's invention 70 serves the roofer's time for nailing the elements since only one nail per shingle is necessary to obtain an efficient roof covering and results in economy of the number of nails necessary to securely apply them to a roof or other surface. 75 The single locking projection 27, together with

locking recesses 25 and 35, serve to securely interlock adjacent shingles together and provide a triangular tab in each of the angles formed at the intersection of the exposed edges of each shingle with an adjacent shingle. Furthermore, the 5 aligning notches 16 and 23, edges 28 and the interlocking recesses 25 and 35 permit laying of the elements with only the necessary lap between the overlying and underlying elements whereby an efficient roof covering is provided.

Since certain changes may be made in the above shingle and in the manner of laying the same without departing from the scope of this invention, it is intended that all matter contained in the above description or shown on the accompanying drawing shall be interpreted at illustrative and not in a limiting sense.

I claim:

1. An interlocking shingle, comprising a substantially square body portion having a locking projection on one corner thereof, said projection being disposed on one side only of said shingle and having one side thereof in line with the said side edge of the said body, said shingle being adapted to be laid with other like elements in overlapping courses with one corner of one element overlapping the opposite horizontal corner of a like element in the same horizontal course, with the said projection of an overlying element passing under the side edge of an underlying element and with the said side thereof in line with the side edge of the said body abutting against a side edge of another underlying element, said projection substantially filling the upper portion of the angle between said side edges of said underlying elements.

2. A roof covering comprising a plurality of shingles, each shingle including a body portion having side edges defining horizontal corners and upper and lower vertical corners, said body portion being provided with a substantially triangular locking projection extending therefrom in the neighborhood of the lower corner and a first locking recess in the neighborhood of a horizontal corner, said projection cooperating with a side edge of the body portion to provide a second locking recess, said shingles being laid in courses with one horizontal corner of each shingle overlapping a horizontal corner of an adjacent shingle in the same course, a side edge of said overlapping shingle cooperating with an edge of the first named locking recess of the underlapping adjacent shingle to form a locking pocket, the second named locking recess of each shingle in an adjacent overlapping course interlocking with a locking pocket in said underlapping course, the locking projection of each of the shingles of said overlapping course extending into each of said locking pockets whereby each shingle of said overlapping course overlaps and underlaps only one underlying shingle and only overlaps another underlying shingle.

3. A roof covering comprising a plurality of shingles, each shingle including a body portion having side edges defining horizontal corners and upper and lower vertical corners, said body portion being provided with a locking projection extending from a side edge thereof adjacent said lower vertical corner and a first locking recess adjacent one of said horizontal corners, said locking projection cooperating with the side edge of the body portion from which it extends to form a second locking recess, said shingles being laid in overlapping and underlapping horizontal courses with one horizontal corner of each shingle,

- overlapping a horizontal corner of an adjacent shingle in the same course, the second named locking recess of each shingle in an adjacent overlapping course interlocking with the first named 5 recess of a shingle of the underlapping course, said shingle of the overlapping course having a portion of its locking projection underlapping only said shingle of said underlapping course with which it is interlocked, the exposed portion 10 of said locking projection having an angular shape corresponding to the angle formed between the intersecting side edges of two adjacent shingles of said underlapping course.
4. An interlocking shingle of general rectangular shape adapted to be laid with other like shingles in overlapping courses with the side corners of contiguous shingles in the same horizontal course overlapping and underlapping, said shingle having a substantially triangular locking projection 15 disposed at the lower corner on one of the two side edges defining the lower corner, the entire area of said projection extending in a direction away from the other side edge defining said lower corner, a portion of said projection being adapted to pass under the side portion of only one of two adjacent shingles of an underlying course and 20 the remaining portion of said projection having an angular shape corresponding to the angle formed between the intersecting side edges of said two adjacent shingles of the underlying course.
- 25

only one of two adjacent shingles of an underlying course to lock the corner of the overlying shingle to said underlying course and the remaining portion of said projection being adapted to be exposed in the angle between said two adjacent underlying shingles and to substantially fill the upper portion of said angle.

5. An interlocking shingle of general rectangular shape adapted to be laid with other like shingles in overlapping courses with the side corners of contiguous shingles in the same course in overlapping and underlapping relation, said shingle having a locking projection disposed at the lower corner on one of the two side edges defining the lower corner, substantially the entire 15 area of said projection extending in a direction away from the other side edge defining said lower corner, a portion of said projection being adapted to pass under the side portion of only one of two adjacent shingles of an underlying course and 20 the remaining portion of said projection having an angular shape corresponding to the angle formed between the intersecting side edges of said two adjacent shingles of the underlying course.
